RACK FOR A PEW BACK

Alfred C. Hoven and Walter E. Nordmark, Grand Rapids,
Mich., assignors to American Seating Company, Grand Rapids, Mich., a corporation of New Jersey

Application August 31, 1959, Serial No. 57,389

Term of patent 14 years

(Cl. D33—3)

Fig. 1

We claim:

The ornamental design for a rack for a pew back, substantially as shown.
